UNITED STATES PATENT OFFICE.

ISAAC JUDSON KELLY, OF OAKLAND, CALIFORNIA, ASSIGNOR TO FAGEOL MOTORS COMPANY, OF OAKLAND, CALIFORNIA, A CORPORATION OF CALIFORNIA.

DESIGN FOR A MOTOR-BONNET.

59,897.

Specification for Design.

Patented Dec. 6, 1921.

Application filed November 19, 1919. Serial No. 339,172. Term of patent 14 years.

To all whom it may concern:

Be it known that I, ISAAC JUDSON KELLY, a citizen of the United States, residing at Oakland, in the county of Alameda and State of California, have invented a new, original, and ornamental Design for Motor-Bonnets, of which the following is a specification, reference being had to the accompanying drawing, forming part thereof.

The figure is a view in side elevation of a motor bonnet, showing my new design.

I claim:

The ornamental design for a motor bonnet as shown.

In testimony whereof I affix my signature.

ISAAC JUDSON KELLY.
